UNITED STATES PATENT OFFICE.

HARRY A. HENDREN, OF SACRAMENTO, CALIFORNIA.

WINDOW SCREEN.

Application filed May 31, 1927. Serial No. 195,313.

My invention relates to window screens, and has particular reference to an improved screen comprising upper and lower sections, which sections cooperate to completely fill the window frame to effectively prevent the ingress of flies or other insects into the room.

An object of my invention is to provide a two-piece window screen comprising an upper and lower section which normally cooperate to cover the entire window opening, and in which the several sections are so associated and mounted that one section can be moved to lie parallel to the other section when it is desired that only one half of the window opening be covered or screened.

A further object of my invention is to provide a two-piece window screen comprising an upper and lower section for normally cooperating to cover the entire window opening and in which the lower section may be removed from the window and the upper section lowered into the position normally occupied by the said lower section when it is desired that only one half of the window opening be covered or screened.

A further object of my invention is to provide a two-piece window screen comprising an upper and lower section which normally cooperate to cover the entire window opening, and in which the upper section is so mounted that it can be moved inwardly and downwardly to lie parallel to the lower section thus to form a double screen, covering only the lower half of the window opening, or, if desired, the lower section may be completely removed from the window frame and the upper section moved downwardly into the position normally occupied by said lower removable section.

A still further object of my invention is to provide a simple, inexpensive and efficient means for permitting the upper section of the screen to be moved inwardly to clear the upper edge of the lower section and downwardly to lie parallel to the said lower section, these movements being permitted through the instrumentality of a pair of double leaf hinges, one end of each of said hinges being pivotally connected to a side member of the frame of the upper screen section and the other end of each of said hinges being pivotally and slidably mounted on vertical guide rods positioned adjacent each side edge of the window frame.

In the accompanying drawings, wherein,

for the purpose of illustration is shown a preferred embodiment of my invention,

Figure 1 is a front elevation of a window equipped with my improved two-piece screen, showing the sections in superposed relation to completely cover the entire window opening.

Fig. 2 is a vertical sectional view on the line 2—2 of Fig. 1,

Fig. 3 is an enlarged fragmental section taken on the line 3—3 of Fig. 1,

Fig. 4 is an enlarged view similar to Fig. 1, but showing in dotted lines how the upper section can be moved inwardly and downwardly to occupy a position parallel to the lower section when it is desired that only the lower half of the window opening be covered or screened,

Fig. 5 is an enlarged view similar to Fig. 3, but showing in dotted lines the action of the double leaf hinge members when the upper section is being moved inwardly preparatory to downward movement,

Fig. 6 is an enlarged fragmental view of the upper screen section showing one of the double leaf hinge members and its associated guide rod, and

Fig. 7 is an enlarged fragmental section on the line 7—7 of Fig. 1 showing the manner of detachably mounting the lower screen section to permit its ready removal from the window frame.

Referring in detail to the drawings, in which like reference characters are employed to designate like parts throughout the several views, the numeral 1 designates broadly a window frame comprising the usual head member 2, side members 3 and sill 4. Upper and lower sash members 5 and 6 respectively are mounted for vertical movement within the frame, it being understood that said sashes are properly balanced by sash weights, (not shown), and that said sashes are guided and confined in their vertical movements by guide strips or beads 7 on the bottom of the head member 2 and on the inner sides of the side members 3. All of the above construction is old and well known in the art and forms no part of my present invention. While I have elected to illustrate my invention as applied to the ordinary sliding sash window construction, it is to be understood that the invention is not limited to use with such construction and that the same may be used with any type of sliding, swinging, or

combined sliding and swinging window sash construction, the invention being particularly well adapted for use in connection with the combined sliding and tilting window sash construction shown in the copending application of Harry A. Hendren and Oscar Karlslust, Ser. No. 189,040, filed May 5, 1927.

The lower section of my improved two-piece screen comprises a rectangular frame member 8 covered with suitable screen material 9 held on the said frame by a retaining bead 10. The outer marginal edge of each of the side frame members of this lower section is cut away to form a vertical channel 11 as best shown in Fig. 7, and this channel cooperates with a bead 12 nailed or otherwise secured to the inner side surfaces of each of the innermost guide strips or beads 7 at opposite sides of the window frame, said channel 11 and bead 12 cooperating to guide the lower section and to maintain the same in parallel spaced relation with the lower window sash 6. In order to maintain the lower screen section in a position parallel to the lower window sash 6 and to permit its ready placement to and removal from such position, I provide the frame 8 with spring projected latches or catches 13 located on opposite sides of the frame, these latches or catches comprising a cylinder 14 inserted within the edge of the frame and having a bullet-shaped member 15 adapted to be forced outwardly by a compression spring 16 and to be moved inwardly against the action of said spring either by movement of a handle 17 or by an inward pull on the screen frame 8 when it is desired to remove the same from the window opening. Suitable handholds 18 are provided in the inner surface of the top and bottom members 40 of the frame 8 and these handholds assist in inserting or removing the frame 8, it being understood that when the said frame is placed in position to cover the lower half of the window opening, the channels or grooves 11 engage the vertically extending beads or guide strips 12 to prevent further inward movement, and the spring latches 13 serve to maintain the said frame in position within the window opening due to the frictional contact between the outer ends of the bullet-shaped bolt members 15 and the side walls of the side beads 7. The upper edge of the top member of the frame 8 is slightly convexed or crowned for a purpose to be hereinafter referred to.

The upper section of my improved two-piece screen comprises a rectangular frame member 19 covered with suitable screen material 20 held on the said frame by the retaining strip 21. The outer marginal edge of each of the side frame members of the upper section 19 is cut away to form a vertical channel 22 as best shown in Fig. 5, and these channels cooperate with the beads or guide strips 12 nailed or otherwise secured to the inner side surfaces of each of the innermost guide strips or beads

7 at opposite sides of the window frame, said channels 22 and beads 12 cooperating to maintain this section in parallel spaced relation with the upper window sash 5 and to maintain said upper section 19 in vertical alinement immediately above the lower section 8. The lower edge of the bottom member 19 is slightly concaved or grooved to accommodate the upper convex or crowned edge of the top member of the lower section 8 when the two sections are placed in vertical alinement as shown in the drawings. Suitable handholds 23 are provided in the inner surface of the top and bottom members of the frame 19 to assist in moving said frame into the desired position.

Positioned at opposite sides of the window frame 1 adjacent each of the innermost side guide strips or beads 7, are vertically extending rods 24, each extending the full height of the window frame and each fastened to the head board 2 and sill 4 by screws or other fastening means. A double leaf hinge member 25 has its two leaves 26 and 27 pivotally connected at their inner ends. The outer end of each leaf 26 is rolled over the rod 24 to form a pivotal and sliding connection therewith, while the outer end of the leaf 27 is pivotally connected to a plate 28 screwed or otherwise fastened to the side member of the frame 19. As will be apparent from an inspection of Fig. 1 of the accompanying drawings, a rod 24 and a double leaf hinge 25 is positioned and secured at each side of the window, the length of the leaves 26 and 27 being such that the section 19 may be moved inwardly from its normal position in vertical alinement with the lower section 8 to a position such as shown in dotted lines in Fig. 5, whereupon said upper section may be moved downwardly along the rods 24 to a position immediately in rear of and parallel to the lower section 8.

Referring now to the operation of the two-piece screen above described, it will be apparent that when it is desired to utilize the construction to completely fill the window frame, the lower section 8 is placed in the frame and moved outwardly toward the lower sash 6 until the channels or grooves 11 abut against the beads 12. During this outward movement, the bullet-like latch members 15 engage the inner surfaces of the innermost guide strips or beads 7 and serve to maintain the said lower section within the window opening in spaced parallel relation to the lower sash 6. The vertical guide rods 24 and their associated double leaf hinges 25 having been secured to the window frame adjacent the innermost guide strips or beads 7, the upper screen section is then placed in the frame and moved outwardly toward the upper sash 5 until the channels or grooves 22 abut the beads 12, at which time the said section 19 is in vertical alinement with the lower section 8 and has its bottom edge rest-

ing on the upper edge of the lower section 8. The plate 28 is then screwed or otherwise fastened to the side frames of the upper section 19.

When it is desired that only the lower half of the window opening be covered or screened or when it is desired to obtain access to the upper sash 5 for the purpose of adjustment, repair or cleaning, the operator's hand engages the handholds 23 and the upper screen section is lifted sufficiently to disengage the convex or crowned upper edge of the lower section from the concaved or grooved bottom edge of the upper sash. The upper sash is then moved inwardly a sufficient distance to clear the lower screen section, at which time the upper section may be moved downwardly along the rods 24 to a position parallel to the lower screen section 8. When in this position, a double screen is formed by the sections 8 and 9 which cover only the lower half of the window opening. When it is desired that only the lower half of the window opening be covered or screened with a single thickness 25 of screen, the operator lifts the upper section 19 upwardly a sufficient distance to disengage the convexed or crowned top edge of the lower section 8 from the concaved or grooved bottom edge of the upper section 19, and by 30 pulling the lower section inwardly with the aid of the handholds 18, the latch members 15 are forced inwardly against the spring 16 and the frictional contact between such latches and the innermost beads 7, is easily 35 overcome to permit the lower section 8 to be readily removed from the frame. If, for any reason, the inward pull of the lower section 8 is not sufficient to slightly depress the spring-pressed latch member 15, the operator, by movement of the operating handles 40 17, may cause said latch members to move inwardly a sufficient distance to overcome any resistance offered to the removal of the lower section from the window frame. After 45 this lower section 8 is removed from the window opening, the upper section 19 is moved downwardly along the guide rods 24 until its bottom edge contacts with the sill 4, at which time the upper section 19 occupies a 50 position previously occupied by the lower removable section 8.

It will thus be seen that I have provided a window screen comprising upper and lower screen sections which are normally arranged 55 one above the other in vertical alinement to completely fill the window opening, the two sections, when in this position, being main-

tained in vertical alinement by means of the guide strips or beads 12 fastened to the window frame and the channels 11 and 22 on the 60 rear surface of the side members of the screen sections 8 and 19. In my improved construction, means have been provided for permitting the upper section to be raised slightly, moved inwardly a sufficient distance to clear 65 the top of the lower section, and then to be moved and guided downwardly to occupy a position parallel to the lower section, such movements being permitted by means of the double leaf hinge members 25 and their associated guide rods 24. I have further provided a novel means for permitting the ready removal of the lower section from the window frame, to permit the upper section to be moved and guided downwardly to occupy the 70 position or space previously occupied by said lower removable section.

It is to be understood that this form of my invention herein shown and described is to be taken as a preferred embodiment of the same and that various changes may be made in the size, shape and arrangement of parts, without departing from the spirit of my invention or the scope of the subjoined claims.

Having thus described my invention, what I claim is:

1. A window screen comprising an upper and lower section normally maintained in vertical alinement one above the other to completely fill the window opening, vertical 90 guide rods mounted at opposite sides of the window opening, and hinge members slidably mounted on the guide rods and pivotally connected to the upper section, whereby said section may be moved inwardly and then guided downwardly to occupy a position parallel to the said lower section.

2. A window screen comprising an upper and lower section normally maintained in vertical alinement one above the other to completely fill the window opening, vertical guide rods mounted at opposite sides of the window opening, and hinge members pivotally connected to each side of the upper section and pivotally and slidably connected to each of the vertical guide rods, whereby said upper section may be moved inwardly a sufficient distance to clear the lower section and then moved and guided downwardly to occupy a position parallel to the said lower 110 section.

In testimony whereof I hereunto affix my signature.

HARRY A. HENDREN.
